AUTOMATIC AIR VALVE FOR STOKERS

Michael Huber, Cincinnati, Ohio, assignor of one-half to Lawrence R. Schmieder, Cincinnati, Ohio

Application December 19, 1939, Serial No. 310,054

7 Claims. (Cl. 251—145)

This invention relates to an automatic air valve for stokers, and has for the primary object the provision of a durable, dependable and controllable device of the above stated character which may be readily adapted to most any type of stoker now in use for regulating the amount of air necessary for a complete and steady combustion of any kind of solid fuel and which will automatically close and thereby shut off draft to the furnace during idle periods of the blower of the stoker, and which may be easily adjusted to vary the amount of air the blower is allowed to expel as forced draft for the fuel and may be easily adjusted to permit the blower to receive a full amount of air at any time it is deemed necessary to have a full amount of forced draft to the burning fuel.

With these and other objects in view, the invention consists in certain novel features of construction, combination and arrangement of parts to be hereinafter more fully described and claimed.

For a complete understanding of my invention, reference is to be had to the following description and accompanying drawings, in which

Figure 1 is a front elevation illustrating an automatic air valve and showing the latter applied to a fragmentary portion of a stoker.

Figure 2 is a top plan view illustrating the same.

Figure 3 is a sectional view taken on the line 3—3 of Figure 1.

Figure 4 is an enlarged fragmentary longitudinal sectional view illustrating the automatic means for closing the valve and the adjustment of said means.

Figure 5 is a sectional view taken on the line 5—5 of Figure 4.

Figure 6 is a sectional view taken on the line 6—6 of Figure 4.

Figure 7 is a view similar to Figure 4 illustrating a modification of this invention.

Figure 8 is a sectional view taken on the line 8—8 of Figure 7.

Figure 9 is a sectional view taken on the line 9—9 of Figure 7.

Referring in detail to the drawings, the numeral 5 indicates a fragmentary portion of a stoker in which is employed the usual blower (not shown). The housing for the blower is indicated generally by the character 6 and the air opening for the blower in the housing is indicated by the character 8. The present invention is so constructed that it may be readily adapted to the housing over the air opening 8 for the purpose of controlling the amount of air to the blower and 55

for automatically closing the opening 8 when the blower ceases to operate. It is to be understood that the present invention is opened under the suction of the blower and is self-closing whenever the operation of the blower of the stoker is stopped which will close natural draft to the furnace with which the stoker is employed.

A valve housing 9 consisting of an annular body 10 is provided at one end with an attaching flange 11 provided with openings to receive stud bolts or like fasteners for rigidly mounting the valve housing onto the housing 6 of the stoker 5. It is preferable that the flange 11 be constructed of large size which will permit the flange to be adapted to various stoker housings in which the draft openings thereof vary as to size, it being understood that when the flange 11 has been adjusted or secured on a stoker housing the surplus portions of the flange may be readily sawed off to give a neat and attractive appearance to the device, as shown at 12.

Attaching lugs 13 are formed integrally with the body 10 adjacent the end thereof opposite to the flange 11 and are located on the interior of the body and are provided with screw threaded openings to receive bolts 14 having finger pieces 15 to facilitate the rotation of the bolts. The bolts are employed for detachably securing on the latter-named end of the body an end plate 16 having a centrally arranged opening 17 aligning with the draft opening 8. The bolts 14 extend through openings provided in the end plate 16.

It is to be noted that the lugs 13 are oppositely arranged on the body consequently bringing about securing of the end plate on the body at opposite sides of the latter.

The end plate 16 about the opening 17 is extended inwardly in the direction of the body for the purpose of forming a valve seat 18 and co-acting therewith is a valve element 19 including a disc-like portion 20 to engage with the seat for closing the opening 17 and a stem 21. The end plate 16 further includes a supporting bar 22 which spans the opening 17 and is provided with a screw threaded opening through which the stem 21 passes freely. The disc 20 is detachably secured on the stem 21 by being positioned between a pair of clamping plates 23, one of which is slightly larger in diameter than the other and is provided with a recess 24 while the other is provided with a projection 25 which extends through an opening in the disc and has the stem 21 extending therethrough. A nut 26 is threaded on the stem and bears against one of the plates 23 the other of the plates being threaded on the stem

consequently firmly anchoring the disc on the stem and providing a connection between these parts which will tend to prevent the disc from buckling.

A bushing 27 is threaded in the opening of the supporting bar 22 and includes a sleeve-like portion 28 provided with openings 29 to permit a spanner-type wrench to be applied thereto for threading the bushing into and out of the opening of the bar 22. The bushing 27 has threaded therein a neck portion 30 of a sleeve 31, the latter being of an increased diameter over the neck portion. The sleeve 31 is externally screw threaded and has threaded thereon a stop sleeve 32, one end of which is notched, as shown at 33, to receive a spanner wrench for the adjustment of the stop sleeve on the sleeve 31. An inner sleeve 34 is arranged within the sleeve 31 and spaced from the major portion thereof and is threaded into the neck 30 of the sleeve 31 and acts as a bearing for the slideable support of the stem 21 of the valve element 19. The free end of the sleeve 34 is notched, as at 35, to permit the application of a spanner wrench thereto. As the sleeve 34 forms a bearing for the stem 21 it is preferable that it be of the lubricating type, that is, treated with graphite or similar lubricant material so as to assure free sliding movement of the stem of the valve under all conditions.

The unattached end of the stem 21 is screw threaded, as shown at 36, to have threaded thereon a sleeve 37 which is arranged to telescope within the sleeve 31. One end of the sleeve 37 has an end wall 38 provided with a threaded opening to thread onto the stem and which forms a seat for one end of a coil spring 39. The coil spring receives therein the stem and the sleeve 34 and its opposite end is seated on a flange on the sleeve 34, which flange abuts the neck 30 of the sleeve 31. The spring is of the expansion type and acts to seat the valve element on the valve seat 18 and by adjusting the sleeve 37 on the stem the tension of the spring may be increased and decreased as desired. Nuts 40 and 41 are threaded on the stem with the nut 40 spaced from the end wall 38 of the sleeve 37, the nut 41 holding nut 40 in adjusted position on the stem.

The sleeve 32, as before stated, acts as a stop by being abutted by the nut 40 for limiting the opening of the valve under the suction of the blower of the stoker. By this arrangement it is possible to regulate the amount of air the blower will receive through the opening 17 in the end plate 16 and consequently regulate the amount of air the stoker furnishes the burning fuels.

A combined guide rod and indicator 43 is secured on the disc 20 and passes freely through an opening 44 in the supporting bar 22 and has threaded thereon a knurled stop 45 located between the disc 20 of the valve and the supporting bar 22 for the purpose of providing a means of varying the closing of the valve with relation to the seat. A scale 46 is provided on the combined guide rod and indicator 43 and when read in conjunction with the bar 22 may indicate to the operator the distance the disc of the valve element will be kept from the valve seat during non-operation of the blower of the stoker. The member 43 extending through the opening 44 besides performing the functions outlined also prevents the valve element from rotating during its movement towards and from the valve seat and consequently obviates any possibility of the stem

rotating and bringing about a twisting or binding of the expansion spring 39.

From the foregoing description when taken in connection with the accompanying drawings it will be understood that, as before stated, the suction of the blower moves the valve element away from the seat and the spring 39 acts to urge the valve element towards the valve seat and that the distance that the valve element may move away from the seat can be easily varied by the operator as well as the distance it may move towards the seat under the influence of the spring permitting a very accurate adjustment of the valve to be had so as to efficiently regulate the proper amount of air to the blower of the stoker to assure proper combustion of the fuel.

A dust cap 47 is arranged over the various sleeves and valve stem and has a frictional fit with the flange 28 of the bushing 27 for the purpose of excluding dirt and other foreign matter from the mechanism confined therein.

Referring to the modified form of my invention, it is proposed to use in conjunction with the spring 39 a magnetic means 48 for the seating of the valve element. In this form of the invention the dust cap 49 is slightly modified from the dust cap 47 and has arranged in its closed end a permanent magnet 50 and coacting therewith is a member 51 subject to attraction by the magnet and is threaded on the stem 36 in lieu of the nut 40. The attraction of the magnet 50 for the member 51 will be for a limited distance therefrom and by the arrangement as described and shown in Figure 7 this magnetic action will take place after the valve has moved a limited distance towards a seated position so that a further movement of the valve element towards a seated position will be under the influence of the magnetic means, the spring 39 of course acting to initially move the valve element towards a seated position.

The arrangement shown in Figure 7 permits the use of a weaker spring than the type of device shown in the other form of my invention and will assure of a positive seating of the valve when the operation of the blower of the stoker discontinues. In small size valves used on small size stokers, the spring 39 may be eliminated and rely on closing of the valve by the magnetic means.

In making the adjustments on the valve for the purpose of limiting the unseating of the valve element from the seat it is preferable to so carry out this adjustment that the valve element when unseated to its limit of adjustment will admit approximately eighty per cent of the entire amount of air to the blower that can be admitted under the construction of this invention and the stoker. If at any time the maximum amount of air is desired, one of the bolts 14 may be removed and the other bolt released so that the end plate 16 and the valve carried thereby may be swung laterally of the valve casing and thereby admit the maximum amount of air to the blower of the stoker.

It is believed that the foregoing description, when taken in connection with the drawings will fully set forth the construction and advantages of this invention to those skilled in the art to which such a device relates, so that further detailed description will not be required.

Having thus described the invention, what I claim is:

1. In a device of the class described, a valve housing, an end wall detachably connected to one

end of said housing and having an air inlet opening therein, and a valve seat surrounding the opening, a valve element including a stem and coacting with said seat and movable away from the seat by suction in the housing, automatic means coacting with the stem for working in opposition to the suction and acting to move the valve element towards the seat, a supporting bar spanning the air inlet opening and carried by the end wall, a bushing threaded in said supporting bar and having the stem extending freely therethrough, a bearing sleeve carried by said bushing and detachable therefrom and slidably supporting the stem, a second sleeve threaded on the stem and housing one end of an expansion type coil spring interposed between said bushing and the second-named sleeve and capable of having its tension varied by the adjustment of the second-named sleeve on the valve stem and adjustable means for limiting movement of the valve element toward opening and closing movements.

2. In a device of the class described, a valve housing having an air inlet opening therein, a supporting bar spanning the opening, a bushing threaded in said supporting bar, a valve element to coact with the seat and movable away from said seat by suction in the housing and including a stem freely received by said bushing, a bearing sleeve threaded in said bushing and slidably supporting the stem, a second sleeve threaded on the stem and housing one end of an expansion spring interposed between the second sleeve and the bushing for urging the valve element towards the seat in opposition to the suction, lock nuts on the valve stem, and a stop sleeve adjustably mounted on the bushing and coactive with one of the lock nuts in limiting the distance the valve element may move away from the seat.

3. In a device of the class described, a valve housing having an air inlet opening therein, a supporting bar spanning the opening, a valve seat surrounding the opening, a bushing threaded in said supporting bar, a valve element to coact with the seat and movable away from said seat by suction in the housing and including a stem freely received by said bushing, a bearing sleeve threaded in said bushing and slidably supporting the stem, a second sleeve threaded on the stem, an expansion spring interposed between the second sleeve and the bushing for urging the valve element towards the seat in opposition to the suction, lock nuts on the valve stem, a stop sleeve adjustably mounted on the bushing and coactive with one of the lock nuts in limiting the distance the valve element may move away from the seat the stop sleeve being telescoped by the second sleeve.

4. In a device of the class described, a valve housing having an air inlet opening therein, a valve seat surrounding the opening, a supporting bar spanning the opening, a bushing threaded in said supporting bar, a valve element to coact with the seat and movable away from said seat by suction in the housing and including a stem freely received by said bushing, a bearing sleeve threaded in said bushing and slidably supporting the stem, a second sleeve threaded on the stem, an expansion spring interposed between the second sleeve and the bushing for urging the valve element towards the seat in opposition to the suction, a stop member adjustably arranged on the valve stem, a stop sleeve adjustably mounted on the bushing and coactive with said stop mem-

ber in limiting the distance the valve element may move away from the seat, said stop sleeve telescopically receiving the second sleeve and means carried by the valve element and coacting with the supporting member in preventing rotation of the valve element and providing a valve position indicator and an adjustable stop means for variably limiting the distance of the movement of the valve element toward the seat.

5. In a device of the class described, a valve housing having an air inlet opening therein, a valve seat surrounding the opening, a supporting bar spanning the opening, a bushing threaded in said supporting bar, a valve element to coact with the seat and movable away from said seat by suction in the housing and including a stem freely received by said bushing, a bearing sleeve threaded in said bushing and slidably supporting the stem, a second sleeve threaded on the stem and housing one end of an expansion spring interposed between the second sleeve and the bushing for urging the valve element towards the seat in opposition to the suction, lock nuts on the valve stem, a stop sleeve adjustably mounted on the bushing and coactive with one of the lock nuts in limiting the distance the valve element may move away from the seat, means carried by the valve element and coacting with the supporting member in preventing rotation of the valve element and providing a valve position indicator and an adjustable stop means for variably limiting the distance of the movement of the valve element toward the seat, and a dust cap removably mounted on the bushing for encasing the major portion of the valve stem, bearing sleeve, second-named sleeve and stop sleeve.

6. In a device of the class described, a valve housing having an air inlet opening therein, a valve seat surrounding the opening, a supporting bar spanning the opening, a bushing threaded in said supporting bar, a valve element to coact with the seat and movable away from said seat by suction in the housing and including a stem freely received by said bushing, a bearing sleeve threaded in said bushing and slidably supporting the stem, a second sleeve threaded on the stem and housing one end of an expansion spring interposed between the second sleeve and the bushing for urging the valve element towards the seat in opposition to the suction, lock nuts on the valve stem, a stop sleeve adjustably mounted on the bushing and coactive with one of the lock nuts in limiting the distance the valve element may move away from the seat, means carried by the valve element and coacting with the supporting member in preventing rotation of the valve element and providing a valve position indicator and an adjustable stop means for variably limiting the distance of the movement of the valve element toward the seat, a dust cap removably mounted on the bushing for encasing the major portion of the valve stem, bearing sleeve, second-named sleeve and stop sleeve, and a permanent magnet located in the dust cap for attracting one of the lock nuts thereto and thereby active to cooperate with the spring in moving the valve element towards a seated position.

7. In a device of the class described, a valve housing having an air inlet opening therein, a valve seat within the housing and surrounding the opening, a bar extending across the opening outwardly of the seat, an inwardly opening valve

member engaging the seat when closed, spring means for holding the valve member in closed position and said valve member moving to open position by suction within the housing, a graduated rod having one end connected with the valve member at one side of the center thereof and the cross bar having a hole therein through

which the graduated rod passes and an adjustable stop on the graduated rod between the valve member and the cross bar and adapted to engage the cross bar to limit movement of the valve member toward the seat.

MICHAEL HUBER.
